UNITED STATES PATENT OFFICE.

THOMAS B. MASON, OF TRENTON, NEW JERSEY.

HORSE-BOOT.

SPECIFICATION forming part of Letters Patent No. 396,167, dated January 15, 1889.

Application filed July 27, 1888. Serial No. 281,194. (No model.)

To all whom it may concern:

Be it known that I, THOMAS B. MASON, of Trenton, in the county of Mercer and State of New Jersey, have invented a new and Improved Horse-Boot, of which the following is a specification, reference being had to the annexed drawings, forming a part thereof, in which—

Figure 1 is a perspective view of my improved horse-boot. Fig. 2 is a transverse section. Fig. 3 is a perspective view of the soft-rubber body of the boot, and Fig. 4 is a transverse section of the same.

Similar letters of reference indicate corresponding parts in all the views.

The object of my invention is to provide a horse-boot which will not absorb moisture, which will retain its form, and which may be readily applied and fastened and easily unfastened and removed.

My invention consists in the construction and arrangement of parts, as will be herein-after fully described and claimed.

The ring A, which is approximately elliptical in form, is provided with a widened side, *a*, and is divided at the opposite side to facilitate placing the ring upon the horse's leg. The inner edge of the ring is provided with flanges *b b'* on opposite sides, and over the flanges *b b'* is stretched a covering, B, of enameled leather or analogous material, which is secured by stitches *c*, passing through the body of the ring outside of the flanges *b b'*. Between the enameled leather covering B and the inner edge of the ring is placed a padding, C, of felt or othersuitable material, which forms a yielding surface.

To the end *d* of the divided ring A is attached a hasp, *e*, which is provided with right-angled ears *f*, secured to the ring by rivets. To the end *g* of the divided ring is attached a plate, *h*, which is bent twice at right angles, and in which is pivoted a button, *i*, consisting of an L-shaped arm loosely riveted in

the plate *h*. The button *i* is capable of passing through the slot *j* of the hasp *e*, and of being turned at right angles through a half-revolution, so as to fasten the two ends of the divided ring, as indicated in Fig. 1 of the drawings. The widened part *a* of the ring A projects sufficiently beyond the horse's leg to prevent interference.

The ring A is preferably made of a solid piece of soft vulcanized rubber; but, if desired to render it more elastic, it may be made hollow, the cavity in the center thereof being filled with air.

In some cases it may be found desirable to omit the cushion from the inner surface of the ring, as shown in Figs. 3 and 4. Therefore I do not limit or confine myself to the exact construction herein shown and described.

Having thus described my invention, I claim as new and desire to secure by Letters Patent—

1. A horse-boot formed of a divided ring having a widened portion, *a*, the hasp *e*, attached to one end of the divided ring, and the plate *h* and button *i*, attached to the opposite end of the divided ring, substantially as specified.

2. In a horse-boot, the divided elastic ring A, having the integral widened portion *a* between its ends, flanges *b b'* on its upper and lower sides at the inner edges thereof, and a fastening for the ends of the ring, substantially as set forth.

3. The combination, with the divided ring A, provided with the flanges *b b'*, of the lining B, secured to the said ring, and the padding C, interposed between the lining B and the inner edge of the ring, substantially as specified.

THOMAS B. MASON.
